GRID DETECTION CIRCUIT FOR WAVE LENGTHS BELOW ONE DECIMETER

Hans Erich Hollmann, Berlin, Germany, assignor to Telefunken Gesellschaft für Drahtlose Telegraphie m. b. H., Berlin, Germany, a corporation of Germany

Application February 21, 1936, Serial No. 65,002
In Germany March 6, 1935

2 Claims. (Cl. 250—27)

By the development of special types of the audion or grid-detector tube the inter-electrode distances have been reduced to microscopically small proportions. It thus becomes possible to 5 use such a tube for wave lengths shorter than one decimeter without incurring any difficulty due to the electron transit times.

It will be understood that a receiver furnished with such a tube must also possess a circuit organization which is adapted to such extremely short waves. A circuit arrangement which has heretofore proved generally suitable for ultra-short wave work and which has come to be known as the "ultra-audion" scheme, I have found to be 10 adapted also to decimeter waves. This circuit arrangement is in fact a "three-point" organization in which a blocking condenser is connected in the node of the oscillation circuit inductance and serves to separate the plate potential from 15 the grid potential in series with the tube capacitance. This blocking condenser, therefore, serves for tuning, and at the same time as a grid condenser.

However, as soon as one gets into the range 20 of half-meter waves and uses short inductance loops this difficulty arises that the capacity of the tuning condenser cannot be made more than a few centimeters if the desired wave is to be obtained. From the viewpoint of separating 25 plate and grid potential, this is immaterial. But considering the function of the grid condenser, a greater capacitance is necessary in combination 30 with the usual grid leaks in order to obtain the requisite smoothing of the potentials.

Now this difficulty is obviated by the present 35 invention as follows: Although the capacitance of the tuning condenser is limited to a few centimeters, a fixed additional capacitor is connected in parallel. The latter is made of the required 40 size of a grid condenser for obtaining satisfactory rectification, say, a few hundred centimeters. In order that the said additional capacitor may not short circuit the tuning condenser, and that it may not react upon the natural wave of the input circuit, the said two condensers must be isolated 45 by high frequency choke coils. The plate potential lead and the grid leak are connected respectively with one and the other of the two plates of the said additional capacitor.

The drawing shows a practical embodiment 50 of the basic idea of the invention in the form of a key diagram. R is the detector tube which, conjointly with the two inductance loops L_1 and L_2 and the series condenser C_1 forms the receiving 55 circuit to which the oscillations picked up by

a suitable aerial are fed. In parallel relation to the variable (tuning) condenser C_1 is arranged the fixed additional capacitor C_2 being isolated for high frequency from condenser C_1 by the aid of the two choke-coils D' and D'' . 5

One plate is brought by way of the grid leak R_g to the cathode, whereas the other plate is connected to the plate potential source E_p by way of the output transformer T. Regeneration may be insured in the customary manner by variation of 10 the cathode heating, of the plate potential, or else of the damping of the oscillation circuit. 10

I claim:

1. A receiving circuit having means including 15 an electron discharge tube for rectifying ultra-high frequency energy, said discharge tube having a cathode, an anode and a grid so disposed in reference to one another that the electron transit times are reduced to a minimum, a resonant circuit including a distributed inductance 20 and an adjustable midget capacitor intercoupling said anode and grid, an inductive and capacitive reactance offering a high impedance to said ultra-high frequency energy in shunt with said midget capacitor, a grid leak resistor in circuit 25 between the cathode and grid by way of a portion of said inductive reactance, and an anode potential source in circuit between said cathode and anode by way of another portion of said inductive reactance which is conductively separated 30 from the first said portion by said midget capacitor and said capacitive reactance. 30

2. An ultra short wave receiving circuit arrangement comprising a rectifier tube having a cathode, an anode, and a control grid, a resonant circuit, the terminals of which are connected respectively to the anode and to the grid of said tube, said resonant circuit comprising a lumped capacitance on each side of which is disposed a distributed inductance constituted by an arcuately formed single conductor, a grid leak circuit 35 connected between said cathode and through one of said arcuately formed conductors to said grid, an anode-to-cathode circuit including an anode potential source and the other one of said arcuately formed conductors, and means including 40 a condenser the capacitance of which is large in relation to that of the capacitance in the resonant circuit for smoothing the rectifier action, the first said capacitance and the last said condenser being shunt-connected, and means for 45 electrically isolating said capacitance and said condenser at the operating ultra high frequencies, said means comprising radio frequency chokes. 50
